UNITED STATES PATENT OFFICE.

AUGUSTINE C. WEST, OF BOSTON, MASSACHUSETTS.

DESIGN FOR A GAS OR OIL STOVE.

SPECIFICATION forming part of Design No. 22,445, dated May 16, 1893.

Application filed March 27, 1893. Serial No. 467,880. Term of patent 7 years.

To all whom it may concern:

Be it known that I, AUGUSTINE C. WEST, a citizen of the United States, residing in Boston, in the county of Suffolk, State of Massachusetts, have invented and produced a new and original Design for Gas or Oil Stoves, of which the following is a specification, reference being had to the accompanying drawing, representing said design.

10 The distinctive features of my design are in the general shape of the stove, which is composed of a rectangular base plate suitably supported, a rectangular box or chamber with a flat overhanging top, the latter being upheld by corner posts or uprights united with the base, and a cylindrical body located at one end of said base.

15 The particular features of my design are embodied in a flat oblong base plate 2 with a similarly shaped chambered portion or box 3 which is supported above upon corner uprights 4. These latter consist of right-angled plates 5. 5. formed with a continuous bead 6 longitudinally of said plate, and constituting 20 a panel, having rounded ends, while a number of circular disks or prominences 8. 8. are arranged therewithin. The ends and the sides

of the stove are open. The box 3 is capped with a flat plate 9, which overhangs said box, and is formed with a molded edge and further 30 constructed with an opening fitted with a circular cover 10, while an open grid - shaped cover 12 surmounts a second opening in the plate 9. This latter is formed longitudinally with open lattice-work 13, as shown. In one 35 end of the base is situated a cylindrical body 14 which connects the base-plate 2 with the box 3. Furthermore this cylindrical body is of reduced diameter in the lower portion, and extends into a closed rectangular vessel 15 beneath said base plate. The supports or legs 16 are curved and are united in pairs by bars 17 having fluted edges and with a central annular ring 18.

40 What I claim is—

45 The design for a gas or oil stove, substantially as described and shown.

In testimony whereof I hereunto set my hand, in the presence of two witnesses, this 25th day of March, 1893.

AUGUSTINE C. WEST.

In presence of—

EDWIN P. JONES,
H. E. LODGE.
